(57) **CLAIM**

We claim the ornamental design for a mobile x-ray apparatus, as shown and described.

DESCRIPTION

FIG. 1 is a front, top and right side perspective view of a mobile x-ray apparatus showing our new design;

FIG. 2 is a front elevational view thereof;

FIG. 3 is a rear side elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the figure views are included for the purpose of illustrating portions of the mobile x-ray apparatus that form no part of the claimed design.
